UNITED STATES PATENT OFFICE

EDMUND KAROLLUS, OF VIENNA, AUSTRIA

FIRE-DAMP PROOF TIME FUSE

Application filed September 29, 1930, Serial No. 485,221, and in Austria September 30, 1929.

This invention relates to a time fuse consisting in the known manner of an electric glow fuse and a detonating cap. A retardation or delay-action fuse contained in a special shell is inserted between the glow fuse and the detonating cap.

Gases are formed during the ignition of the said fuse. These gases must be quickly discharged, otherwise the shells containing the fuse would burst. A pointed flame is produced which immediately ignites the blasting charge whereby the action of the time fuse, which consists in retarding the ignition of the blasting charge, will be annulled.

15 However, the chief drawback of the formation of the said pointed flame resides in the fact that this flame is adapted to ignite fire damp.

A large number of arrangements or systems 20 have become known which have for their object to quickly expand the gases formed during the ignition of the fuse and to cool them during the expansion so that a pointed flame can no longer be produced.

25 For this purpose, porous material (filters) of non-inflammable matter in the form of plugs or fillers are provided in the path where the gases are expanded.

Practical experience has shown that it is 30 not immaterial where these porous materials (filters) are provided and in which direction the gases are led. The filter materials must present only slight resistance to the advancement of the gases. The filter materials must 35 be so shaped and arranged that they cannot be compressed by the gas pressure to such an extent that they form an obstruction for the passage of the gases or close the perforations of the fuse.

40 The openings of the fuse, through which the gases escape into the bore hole chamber, must be provided in such places of the fuse so that they cannot be covered externally.

All time fuses have the last drawback, 45 wherein the openings are directed in the bore hole chamber on the obstruction side. The drawback that parts of the filter material are forced internally against the outlet openings into the bore hole chamber and partially close same is to be found in most of those

arrangements or systems wherein the said outlet openings are closed for protection against moisture or impurities externally. The inner pressure must increase until the plug or the like is forced away or burnt. The path for the gases is then suddenly opened and the gases entrain parts of the filter material into the opening which is again closed. This process frequently causes a bursting of the shell of the fuse and the formation of a 60 pointed flame.

These drawbacks are obviated by the present invention by the following arrangement or system.

Figure 1 shows a longitudinal sectional view of the invention.

Figure 2 shows a longitudinal sectional view of a modification of Fig. 1, showing the ribs 11.

Figure 3 shows a cross sectional view thru 70 the rib section 11 of Fig. 2.

The shell 4 (Figure 1) contains in its upper part the electrically ignitable composition 1, below which there is a plug 12 composed of glass-, slag-, or asbestos wool and 75 provided with a central bore 13 wherein a tube 14 is inserted which does not extend to the ends of the bore. During the ignition, the pointed flame coming from the electric fuse may freely strike through the said tube 80 and reach the retardation fuse 5 which is provided in the retarder 2. The retarder 2 is surrounded by the shell 8 which has a flange 10. The shell 4 is mounted on the shell 8. The shell 8 is of such dimensions that a 85 space is left between it and the shell 4. The shells are fixed by a center-mark 6 so that the plug 12 of the shell 4 firmly bears against the retardation fuse 5 and a rigid connection is formed between 4 and 8.

The end of the shell 8 directed toward the detonating cap 3 is slightly conical-shaped so that the shell 7 of the detonating cap 3 bears tightly on the said conical part of the shell 8 and the shell 8 cannot pass to the composition of the cap.

According to the constructional form shown in Figures 2 and 3, the shell 8 has longitudinal ribs 11 so far as it is inserted 11 in the shell 4.

It is advisable to provide the shell 4, on its lower end opposite the flange 10 with notches or the like.

The fuse operates as follows:

- 5 As soon as the composition 1 of the electric fuse is ignited, the pointed flame thereof strikes through the tube 13 so the retardation fuse 5 which burns and ignites the composition of the detonating cap 3.
- 10 The excessive gases can immediately pass from the electric fuse 1, then above and below the tube 14 and from the retardation fuse 5 into the plug 12 without any obstruction; the gases are cooled therein and can
- 15 freely pass to the chamber between shell 4 and shell 8 whence they issue past the edge 9 of the flange 10 into the bore hole chamber. This part of the bore hole chamber is always uncovered and a free exit of the gases
- 20 is therefore also possible. It is possible by this arrangement to prevent a bursting of the shell and the formation of a pointed flame.

According to the present invention, it is possible to obtain a uniform, frictionless degassing free from a pointed flame in the space always remaining free between composition and charge so that the duration of combustion of a time fuse is maintained up to $\frac{1}{16}$ part of a second and not only a premature explosion of the blasting charge is avoided but also the security of the fire-damp is increased.

What I claim is:

- 25 Fire-damp proof time-fuse with a filter layer preventing the formation of a pointed flame, characterized in that the filter-plug made of non-inflammable fibrin in the known manner is arranged between the electrically ignitable composition and the retarder and
- 30 is provided with an axial bore, into which a tube is inserted but which does not extend to the ends of the bore in order to lead the pointed flame from the glow-fuse to the retarder.

35 In testimony whereof I affix my signature.
EDMUND KAROLLUS.
